(57) **CLAIM**

The ornamental design for an environmental controller housing, as shown and described.

DESCRIPTION

FIG. 1 is a perspective view of an environmental controller housing with a display;

FIG. 2 is a perspective view of the environmental controller housing of FIG. 1, with a first illustrative arrangement of buttons below the display;

FIG. 3 is a perspective view of the environmental controller housing of FIG. 1, with a second illustrative arrangement of buttons below the display;

FIG. 4 is a perspective view of the environmental controller housing of FIG. 1, with a third illustrative arrangement of buttons below the display;

FIG. 5 is a front elevation view of the environmental controller housing of FIG. 4; and,

FIGS. 6-10 are back, left, right, top and bottom views of the environmental controller housing of FIG. 4.

The portions illustrated in broken lines on the figures are for illustrative purposes only and form no part of the claimed design.
